UNITED STATES PATENT OFFICE.

VICTOR P. DE KNIGHT, OF WASHINGTON, DISTRICT OF COLUMBIA, AS-SIGNOR, BY DIRECT AND MESNE ASSIGNMENTS, TO THE VICTOR P. DE KNIGHT GUN COMPANY, OF WASHINGTON, DISTRICT OF COLUMBIA, A CORPORATION OF DELAWARE.

AUTOMATIC RAPID-FIRE GUN.

SPECIFICATION forming part of Letters Patent No. 698,107, dated April 22, 1902.

Application filed July 20, 1898. Renewed October 29, 1900. Serial No. 34,803. (No model.)

To all whom it may concern:

Be it known that I, VICTOR P. DE KNIGHT, a citizen of the United States, residing at Washington, in the District of Columbia, have invented certain new and useful Improvements in Automatic Rapid-Fire Guns; and I do hereby declare the following to be a full, clear, and exact description of the invention, such as will enable others skilled in the art to which it appertains to make and use the same.

This invention relates to breech-loading ordnance, and particularly to the construction of rapid-fire machine-guns wherein the gas evolved in each discharge is utilized as a motive force to continue the operation of the gun and cause successive discharges to take place automatically, although some of the novel features hereinafter described may be embodied in other types of guns.

Compactness of construction, a minimum number of parts, stability of the same, lightness in weight of the moving parts, accessibility to all the parts, and provision for accuracy and sureness in the operation of the gun are desiderata which have been kept constantly in view in the evolution of the present invention, the latter consisting in a number of novel constructions and combinations of elements set forth in the appended claims.

The drawings which accompany and form part of this specification illustrate a preferred form of embodiment of the invention and of said drawings.

Figure 1 represents the gun in longitudinal section with the parts in the relation they maintain when the gun is not in operation, but ready to fire. Fig. 2 is a similar view in which the parts appear in the relation they assume immediately after a discharge when reloading is in progress. Fig. 3 is a cross-section taken on the line III III of Fig. 1 looking in the direction of the arrow crossing said line. Fig. 4 is a cross-section taken on the line IV IV of Fig. 2, this view and Fig. 3 being on an enlarged scale as compared with Figs. 1 and 2 and the section-line being staggered. Fig. 5 is a cross-section taken on the line V V of Fig. 4. Fig. 6 is a cross-sectional

front elevation of the device for extracting the cartridge from the belt, which device appears in side elevation in Figs. 1 and 2. Fig. 7 shows this device in bottom plan view, together with some parts in the immediate vicinity. Fig. 8 represents in perspective an end portion of the cartridge-belt. Figs. 9 and 10 are fragmentary longitudinal sectional views illustrating the trigger, sear, and breech-block lock on an enlarged scale, together with coöperating parts, Fig. 9 showing the relation of parts when the gun is not firing and Fig. 10 showing the relation of parts when the gun is firing. Fig. 11 shows a portion of the gun in horizontal section, illustrating the cartridge-feeding mechanism as it would appear when the operating parts are in the relative positions shown in Fig. 1. Fig. 12 is a fragmentary vertical longitudinal section illustrating the devices for guiding or pointing the cartridge in loading, these devices being in the relation they assume when the parts connected with the gas-operated plunger or piston have advanced a short distance under the influence of the retractile springs. Fig. 13 is a horizontal section of the front lower portion of the receiver of the gun, a cartridge being shown in position to be shoved into the barrel and dotted lines representing an advanced position of the cartridge such as to permit its dropping into line with the bore of the barrel. Fig. 14 is a horizontal section of a still lower portion of the receiver, illustrating shell extracting and ejecting devices. Fig. 15 is a similar section taken on a different plane and with the parts in a different relation. Fig. 16 is a detail perspective view of a spanner for removing the rear closure of the piston-cylinder. Fig. 17 is a similar view of an instrument employed for extracting the piston or plunger after removal of said closure, the upper portion being broken away to illustrate the construction of the instrument. Fig. 18 is a detail perspective view of a broken-off portion of a rod employed as a handle in connection with said spanner and piston-extracting device. Fig. 19 is a perspective view of the reciprocating gas-impelled structure, repre-

sented as broken away at one place and a portion of the structure separated from the remainder for better illustration. Fig. 20 is a cross-section on the line XX XX of Fig. 10.

- 5 Fig. 21 is a cross-section of the breech-block, taken on the line XXI XXI of Fig. 19. Fig. 22 is a perspective view of the rear closure of the gas-cylinder. Figs. 23 and 24 are perspective views of members of the cartridge-feeding mechanism. Figs. 25 and 26 are perspective views of members of the cartridge-pointing mechanism. Fig. 27 is a perspective view of the stationary support for the retractile springs, portions of said springs being shown in connection with said support. Figs. 28 and 29 represent in perspective and separated from each other the sear, the breech-block lock, and part of the trigger. Fig. 30 is a perspective view of a modified form of 15 stock or receiver casing. Fig. 31 is a longitudinal vertical section of the same, showing a modified arrangement of parts within. Figs. 32 and 33 are perspective views of the sear and lock of this modified construction. Fig. 34 is a cross-section, on an enlarged scale, taken on line XXXIV XXXIV of Fig. 31. Fig. 35 is a plan view of part of the trigger connections shown in Fig. 31. Fig. 36 is a horizontal section illustrating a modified form 20 of cartridge-feeding mechanism, and Fig. 37 is a cross-section on the line XXXVII XXXVII of Fig. 36.

The gun is here shown adapted to be supported upon a tripod, which may consist of 35 legs *a*, jointed to a tubular socket *a'*, receiving the stem of a forked post *a''*, the upper portions of whose arms are formed as bearings, (see Fig. 4,) in which trunnions *b* are journaled, these trunnions being formed upon 40 the sides of the receiver *b'* of the gun. A screw *a''* is pivoted at one end to an ear on the stem of said post, and a turnbuckle *a'''* engages said screw and is swiveled to a knuckle *a''''*, pivoted to an appropriate part of the gun, 45 so that by turning the said turnbuckle the gun may be tilted on its trunnions *b*, and thereby sighted. The solid lower front portion of this receiver, from which these trunnions project, is longitudinally bored and 50 screw-threaded, as shown at *b''*, and the gun-barrel *c* is screwed home in this bore of the receiver, its inner end being flush with the shoulder formed by the inner end of the said solid lower front portion of the receiver. The 55 front end of the receiver is formed with an exteriorly-screw-threaded hollow boss or flange *b''''*, and the flanged inner end of a jacket *d* abuts the end face of said hollow boss, a clamping-collar *d'* taking over the 60 flange of said jacket and engaging the screw-threads of the boss, so as to hold the jacket tightly against the same. The said jacket is of generally cylindrical form, but tapers slightly toward its forward end, which is 65 closed and through which the barrel *c* protrudes, said barrel where it passes through the end of the jacket being slightly thickened

and screw-threaded, as shown at *c'*, and a screw-threaded collar *c''* being applied to said portion *c'* and against a shoulder *c'''* on the 70 barrel and tightly fitting an opening made for it in the end of the jacket. A flanged clamping-collar *c'''* fits over the end of the barrel and is internally screw-threaded to engage the screw-threaded portion *c'* of the barrel, 75 and said clamping-collar abuts the outer end of the collar *c''*. By the above-described construction the outer end of the barrel is securely fastened to the jacket and an effective closure of the latter is provided around the 80 barrel.

At an appropriate point within the jacket the barrel *c* is formed upon its upper side with a boss *c''*, having a central bore *c'''*, which communicates with the bore of the barrel, so that 85 after the ball has passed the port formed in the upper side of the gun-barrel by this bore *c'''* gas may escape from the gun-barrel into the latter. A bent pipe *e*, contained within the jacket *d*, is formed at its forward end with a circular head *e'*, which bears upon the top of the boss *c''* and has a transverse opening through it which is screw-threaded to receive a plug *e''*, also engaging a screw-threaded socket in said boss, so that this plug constitutes a means of 90 connection between the barrel and the pipe. This plug is formed with a longitudinal bore *e'''*, alining with the bore *c'''* in the boss, and also has a radial bore *e''''*, which alines with the bore of the pipe *e*, the location of this radial bore being such that when the plug is screwed home alinement of the radial bore and the bore of the pipe will follow. A screw *e''''* is entered through one side of the head *e'* on the pipe *e* and is formed with a reduced 95 plain end portion *e'''''*, which enters a continuation of the radial bore *e''''* and is adapted to constitute a valve or choker to regulate the amount of gas passing into the pipe *e* from the gun-barrel. This pipe *e* is compounded with a cylinder *e''''''*, positioned in the rear upper portion of the jacket *d* and having an interior diameter much greater than the interior diameter of the pipe, the small interior diameter of the pipe decreasing the 100 volume of air to be displaced by the gas and so quickening the action. The rear end of this cylinder is formed with exterior screw-threads, as shown at *e''''''*, for engagement with interior screw-threads of a boss *b''''*, formed 105 upon the front of the receiver *b'*, in connection with the flange *b''''*, hereinbefore mentioned. The cylinder *e''''''* has a squared portion *e'''''''*, and the jacket *d* has a pair of lugs *c''''* on its interior, which coöperate with said squared portion of the cylinder, as illustrated 110 in Fig. 3, to prevent the jacket from turning. This jacket is intended to contain a supply of water to keep down the temperature of the gun-barrel and the gas-conduit, and an inlet-opening is formed in the jacket, preferably at the upper rear portion of the same, as shown at *c''''''* in Fig. 3, and a suitable stopper *c'''''''* is provided for said inlet-opening. An

outlet-opening is provided at the forward lower portion of the jacket, as shown at c'' in Fig. 1, and a stopper c^{10} is provided for this outlet-opening.

5 A plunger or piston f fits snugly within the cylinder e^8 , this piston being preferably hollow, as shown in Fig. 2, with one end closed by a screw-plug f' , so as to reduce weight as much as possible, and thereby increase 10 promptness of action, and the other end formed with a mushroom-shaped head f^6 , for a purpose which will presently appear. The rear end of the cylinder is closed by a screw-threaded plug f^2 , which engages screw-threads 15 in a continuation of the bore of the boss b^4 , and this plug is formed with a number of perforations f^3 , which prevent the formation of an air-cushion or a vacuum in the rear end of the cylinder, which would impair the 20 operation of the piston or plunger therein. These openings are utilized in the removal of the plug for cleaning or other purposes, a spanner, such as shown in Fig. 16, being employed and consisting of a disk f^4 25 and pins f^5 thereon, adapted to engage a pair of openings in the plug. An implement, such as shown in Fig. 17, is employed for removing the piston or plunger, comprising a cylindrical body portion f^7 , a pair of catches f^8 30 for engaging the mushroom-shaped head f^6 of the plunger, pivoted to said body within suitable recesses, and a spring f^{11} , contained within a transverse opening in said body portion and pressing the outer ends of the 35 catches toward each other. A rod f^9 of appropriate length is employed in connection with the above-described spanner and piston extracting implements, said rod being formed with a squared end portion f^{10} for engagement with a squared opening f^{10} in the disk of the spanner, and beyond said squared portion is a screw-threaded end portion f^{12} , adapted to engage a screw-threaded socket f^{13} in the body portion of the extracting 40 implement. (Shown in Fig. 17.)

A rod g slides through the plug f^2 , its forward end entering the cylinder and abutting the head of the piston therein, and said rod is preferably made hollow and closed at its 45 ends by screw-plugs, as shown at g' in Figs. 2 and 11. This rod constitutes part of a structure which is reciprocated after each discharge of the gun, this structure being driven back by the pressure of gas against the piston f and being advanced by the retractile force of spiral springs g^2 , which at their forward ends are engaged with a round cross-piece g^3 , located at the upper forward corner of the receiver, this cross-piece being shown 55 in detail in Fig. 27. At their rear ends these springs are connected by a yoke g^4 , which embraces a bifurcated upstanding arm g^5 on a block g^6 , which is interiorly screw-threaded, as shown in Fig. 11, to receive the exteriorly 60 screw-threaded rear end of the rod g , the connection between the block and rod being made secure by means of a set-screw g^7 , entered

through one side of the block and engaging the rod. This block is formed on each side with bifurcations g^8 , which engage guiding-strips g^9 , extending along the side walls of the receiver, turning of the rod or parts attached thereto being thereby absolutely prevented. 70

The rear end of the gun-stock is formed by a substantial wedge-block h , which is vertically grooved at the sides, as shown at h' in Fig. 11, for engaging with vertical strips or ribs h^2 , formed on the sides of the receiver, said block being adapted to slide down into place and being readily removable after the 80 top plate b^5 of the receiver has been detached. The block h may receive the blow of the rod g without cushioning means; but I prefer to incase a comparatively stiff spring h^3 within the block and between a screw-plug h^4 , closing the rear end of the chamber containing 85 said spring, and the head of a buffer-pin h^5 , which normally protrudes from the front face of the block, as shown in Fig. 1, so as to receive the blow of the rod. This blow is due, 90 of course, to the operation of the gas against the piston f , and as a rearward stroke of the rod is necessary to the loading of the gun manipulative means must be provided to effect a rearward stroke of the rod at the outset, and the means here shown for this purpose comprise a handle or pull i , carried by the block h , and a rod i' , compounded with said handle and sliding through an opening in the upper part of said block and passing through the bifurcation of the arm g^5 on the block g^6 , which, it will be remembered, is firmly secured to the reciprocating rod. The said rod i' is formed with a round head i^2 , (see Fig. 19,) adapted to abut the front side of the bifurcated arm g^5 upon said rod i' being drawn out by a pull upon the handle i , and thus it will be seen that manipulative means are provided for effecting a rearward stroke of the rod, so that at the outset the gun can be loaded, it being understood that thereafter the loading takes place automatically. I also provide for operation of the gun by hand in case of an emergency, provision being made for effecting a forward stroke of the rod g by manipulation of the 115 handle i , as well as a rearward stroke, so that by working said handle in and out rapid firing of the gun can be manually effected. To this end the rod i' is formed at a short distance back of the head i^2 with a cross-head i^3 , 120 which normally stands vertically, and thus positioned will freely pass through the bifurcation of the arm g^5 ; but by turning the rod i' this cross-head will be brought to a position where it will abut the bifurcated arm, and 125 therefore by drawing the rod i' rearwardly until the head i^2 abuts the front side of the bifurcated arm g^5 and then turning the said rod through an angle of ninety degrees the cross-head i^3 will be positioned to abut the 130 rear side of the said bifurcated arm, and these parts are so interlocked that by reciprocating the handle i the rod g will be reciprocated in an obvious manner. In its normal position

against the block h the handle i is held vertical by reason of a pin i^4 on its lower end engaging a socket formed for it in the block h , and of course the handle must first be drawn 5 out far enough to disengage said pin from said socket before it can be turned.

The cartridges are fed to the gun in a belt which is composed of strips of canvas j , connected by transverse rows of stitching, between 10 which pockets are formed to receive the cartridges 2, the belt being adapted to embrace the central portions of the cartridges, so that the latter can project to a considerable extent on each side of the belt, the purpose 15 of which will hereinafter appear. The cartridge-belt passes transversely through the front portion of the receiver, entering through an opening j' in one side thereof, which opening is sufficiently wider than the length of a 20 cartridge to permit the latter to pass freely through it, said belt passing out of the receiver through an opening j'' in the opposite side of the latter of considerably less width than the length of a cartridge and adapted to 25 be conveniently closed to exclude dust and dirt when the gun is not in use by a hinged shutter j^2 , as shown in Fig. 4. The bottom of the passage-way through the receiver between the openings j' and j'' is channeled, as 30 shown at j^{11} , to accommodate the belt j , while the cartridges ride upon the ledges j^{12} left along each side of the channel. The bottom of the outlet-opening j'' is a continuation of the bottom of said channel, as shown in Fig. 4, while 35 the ledges form part of the bottom of the inlet-opening j' and terminate at vertical shoulders j^{13} within the receiver and against which the cartridges abut by reason of their projection at each side of the belt, these shoulders 40 and ledges forming a kind of throat to receive the cartridge. In order to prevent a cartridge from rising after it has entered the throat, a pin j^{14} projects from the rearmost one of the vertical shoulders j^{13} and is slightly 45 inclined, so that the cartridge will readily enter beneath it, as shown in Fig. 4. A casing j^3 , rectangular in cross-section, as shown in Fig. 5, is fastened to the receiver around the opening j' in the side thereof, said casing being 50 flanged for the purpose and its interior shaped like said opening. The bottom of the casing has a channel j^{15} , alining with the channel j^{11} in the receiver, and side ledges j^{16} alining with the ledges j^{12} , the ledge at one side being 55 higher than that at the other, so that the cartridge, resting with its flanged head on one ledge and its ball on the other, will be held horizontal, as shown in Fig. 5. The sides of the casing are somewhat broadened at the outer 60 lower portions, as shown at j^4 , and support a roller j^5 , over which a belt of cartridges travels, as clearly illustrated in Fig. 4, and in the top of the casing there are formed parallel longitudinal grooves j^6 , which are undercut, as 65 shown at j^7 , and receive the arms k of a slide whose inner portion k' , connecting said arms, projects into the receiver and is jointed by a

slot-and-pin connection (shown at k^8) to a lever k^3 , pivoted at k^4 to the receiver-casing and adapted to vibrate in a horizontal plane, 70 said lever being impelled in a direction to move the slide outwardly by a flat spring k^5 , which is fastened at one end to the lever and bears near its other end against one side wall of the receiver. This lever carries an anti-friction-roller k'' , which bears against the edge of a cam-piece k^6 , which is formed with or may be fixedly attached to a block m , affixed to the rod g , the said cam-piece having an incline k^7 , which runs down from the highest part of the cam-piece toward the forward end of the rod and practically merges into the surface of the latter, so that upon the rod being moved rearwardly the spring k^5 may operate to move the lever on its pivot and thereby cause the slide to move outwardly. Of course upon the reverse movement of the rod g the incline k^7 , acting against the roller k'' , will move the lever against the tension of the spring k^5 , and consequently draw the slide inwardly. When the lever is constructed with a tailpiece k^8 , as shown in Fig. 11, the cam-piece will be made with an incline k^9 on a reverse angle to the incline k^7 and adapted to encounter the tailpiece k^8 upon a rearward movement of the rod g , so that instead of relying upon the spring k^5 to move the slide outwardly the outward movement of the latter will be effected positively. However, this tailpiece on the lever is not essential and may 90 well be dispensed with, as the spring will ordinarily accomplish the outward movement of the slide in a thoroughly-effective manner. The arms k of the slide are formed on their inner sides with flanges k'' , which occupy the 95 undercut portions j^7 of the grooves j^6 , whereby the arms are properly held up in said grooves, and said arms are slotted longitudinally, as shown at k^{12} , to receive feed-dogs k^{13} , which are pivoted in the outer ends of the 100 slots and formed to abut the rear walls of the latter, so that their downward movement is properly limited, these dogs being adapted to drop far enough to effectively engage the cartridges where they protrude from the sides 105 of the belt. Flat springs k^{14} are fastened in recesses formed as continuations of the slots, and said springs bear upon the upper edges 110 of the feed-dogs and press the same downwardly, so as to hold them in position for engagement with the cartridge during the inward movement of the slide. Upon the outward movement of the slide the said springs yield, so that the dogs will pass easily over the cartridge to be next advanced by them. In 115 view of the fact that the feed-dogs act against the next cartridge to the one fed into the throat of the receiver, the belt is equipped at its tail end with an abutment-piece for the dogs, or one of them, to engage in feeding the 120 last cartridge into the throat, this abutment-piece, as shown in Fig. 8, being in the form of a flat spring 3, fastened to a metal clip 4, which is secured to the canvas strips j . The

spring projects from the clip sufficiently to be engaged by one of the feed-dogs and will yield sufficiently when it encounters the shoulder j^{13} (shown in Fig. 4) to permit the belt being pulled out of the receiver after the last cartridge has been extracted from it. In order to prevent backward movement of the cartridge-belt, catches k^{16} are pivoted in recesses formed in the ledges j^{16} , and springs k^{15} are arranged to press said catches upwardly, so that they stand behind the cartridge next to the one being extracted, as shown in Fig. 4, and thereby prevent backward movement of the cartridge-belt, upward movement of the said catches being limited by their abutment against the rear ends of the recesses.

The block m , hereinbefore referred to as mounted upon the rod g , is affixed thereto by means of a set-screw m' , (see Fig. 19,) and its rear side abuts a half-collar or segment m^2 , brazed or otherwise fastened to the rod and formed in one piece with a rib m^3 , extending along the upper side of the rod and also secured thereto integrally with a collar m^4 , which surrounds the rod. Thus the block is well backed up, and said screw m' is not relied upon to resist end thrusts. The block carries on one side a roller m^5 , which travels in contact with one side wall of the receiver and prevents warping of the rod g by the lateral strain put upon it in the operation of the feed mechanism above described. The block m is vertically grooved in opposite sides and across the top, and in the side grooves fingers m^6 are pivoted, said fingers having outwardly-extending portions or heels m^7 at their upper ends, which are acted upon by a flat spring m^8 , lying in the top groove of the block and secured to the latter at the middle, this single spring thus acting to press the fingers toward each other and normally hold them against the bottoms of the side grooves. The lower portions of these fingers are disposed obliquely, so that their rearmost edges m^9 are nearer together than their forward edges, said rearmost edges being adapted to engage the flange of the cartridge in extracting the same from the belt. In the forward movement of the rod g the inner oblique faces of the fingers are carried into contact with the flange of the cartridge, and the flat spring m^8 allows said fingers to open slightly, so as to permit their rear edges m^9 to pass by the said flange, whereupon they snap in front of the same, so that upon the rearward movement of the rod they will operate to extract the cartridge from the belt. At a suitable elevation spurs m'' are formed on the rear edges of the fingers, and they operate to prevent the cartridge from moving above its proper position when being extracted from the belt.

In the bottom of the receiver there is formed a longitudinal cylindrical chamber or slide-way n , which is in alinement with the barrel, but which has a bore of much larger diameter than that of the barrel, said chamber at its forward end being adapted to receive the car-

tridge after the same has been extracted from the belt and carried rearwardly. In the upper side of this chamber, just back of the barrel, an opening n' is made, of sufficient size to permit the passage of a cartridge through it into the chamber, except at the rear end of the opening, where elongated lugs or protuberances n^2 at opposite sides effect a contraction thereof sufficient to prevent the flange of the cartridge from passing through when in its rearmost position. This is well illustrated in Fig. 13, which also shows in dotted lines a position of the shell indicating that when moved forward the shell may drop through the opening as soon as its flanged head has cleared the projections n^2 . At a short distance back of the rear end of the opening n' a cartridge-depressor arm or lever o is pivoted at o' to a fixed portion of the receiver bridging the chamber n , said arm normally standing inclined upwardly, so that the extractor-fingers m^6 carry the cartridge underneath the arm, the said fingers passing on either side of the latter and the cartridge by contact with the lower side of the lever being caused to move downwardly between the said fingers, but not to be entirely released therefrom. A projection o^2 on the upper side of this arm or lever near its pivot stands in the path of a pivoted cam-piece or wiper o^3 , carried by a rearward extension o^4 of the block m , this extension of the block running along the under side of the rod g . Said wiper is normally held in an oblique position by a flat spring o^5 , (see Fig. 7,) fastened to one side of it at the rear end and bearing at its forward end against a hook o^6 , secured in the block m and depending therefrom, the said spring pressing the wiper against a pin o^7 , fastened in the under side of the block m . This oblique position of the wiper causes its side edge opposite that where the spring is located to encounter one side of the projection o^2 on the arm o as the rod g moves rearwardly, and the wiper is therefore displaced by reason of the yielding of the spring o^5 , so that it passes by the said projection o^2 without affecting the arm o , which remains in its upward inclined position during the rearward stroke of the rod g ; but upon the advance of the said rod the forward end of the wiper o^3 encounters the projection o^2 , it being understood that as soon as this wiper passes the projection o^2 in the rearward stroke of the rod it snaps back to its normal position, wherein its front end or one corner of it is in line with the projection o^2 . The upper side of the said projection is slightly beveled, as is also the corner of the wiper which encounters said projection, and the effect of the encounter between these parts is well illustrated in Fig. 12, the arm o being depressed, while the bottom surface of the wiper o^3 rides along the top surface of the projection o^2 , so that the arm or lever o is positively held in its depressed position with its front end alining with the upper side of the bore of the gun-barrel and constituting a guide for pointing.

the cartridge and insuring its entry into the bore of the barrel in a proper manner, to which end the underside of the arm is dished or grooved to conform with the curvature of the cartridge.

In order to prevent warping the rod g by reason of the positive action of the wiper o^3 against the projection o^2 , I provide a lug o^8 on the under side of the cover-plate b^5 , which lug depends sufficiently for engagement with the strip m^3 , running along the upper side of the rod g , this engagement continuing as long as the cam-piece and projection o^2 are in contact, and the lug o^8 thus resisting any tendency to warping the rod g .

The chamber n constitutes a slideway for a breech-block p of cylindrical form and having an upstanding arm p' , which projects through a longitudinal slot p^2 in the upper side of the chamber n and is formed at its upper end into a collar p^3 , loosely embracing the rod g between the collar m^4 and the block g^6 , between which there is a sufficient space to permit movement of the rod independent of the breech-block, so that in movement of the rod g in each direction it advances a distance before the breech-block is moved. This breech-block is grooved in its upper side at the front, as shown at p^4 , the groove terminating at its rear end in a cam-surface p^5 , which in the forward movement of the breech-block encounters the curved or beveled rear edge of a lug p^6 , formed on the under side of the arm o adjacent to the pivot thereof, whereupon by upward movement of the arm is effected, so that when the breech-block is in the forward position, as shown in Fig. 1, the lug p^6 rests upon the upper surface of the breech-block back of the groove p^4 , and the arm o is thereby maintained in its normal upwardly-inclined position. When the breech-block is in its rearward position, as shown in Fig. 2, the groove p^4 is below the lug p^6 , and hence when the wiper o^3 acts against the lug o^2 to depress the lever o the lug p^6 moves into the said groove, as shown in Fig. 12; but before the wiper so acts the friction between the extractor-fingers m^6 and the cartridge supports the arm o in its upward inclined position, as shown in Fig. 2. It is preferable to provide means for positively limiting the rocking of the arm o , and this I accomplish by means of oppositely-extending fingers o^9 , formed upon a pivot-sleeve of the arm, as shown in Fig. 26, the ends of said fingers being adapted to encounter the bottom of the receiver-chamber, whereby the correct cartridge guiding or pointing position of the arm is assured and the arm is prevented from moving upward far enough to interfere with the operation of the gun. When the rod g advances, the fingers m^6 retreat from the flange of the cartridge as the cam-piece o^3 encounters the projection o^2 , and the cartridge assumes an inclined position, such as shown in Fig. 12, its head resting upon the protuberances n^2 in the opening n' .

A lever r , pivoted to the under side of the receiver, projects at its forward end through an opening therein and is formed with a dished head r' to receive the front or ball end of the cartridge and properly point it for entry into the gun-barrel. The rear end of the lever r projects into another opening in the under side of the receiver and is formed with a finger r^2 , which when engaged by the under surface of the breech-block at the forward part of the latter is sufficiently depressed to produce an elevation of the dished head r' within the chamber in front of the breech-block to properly position said head for receiving the front end of the cartridge and properly pointing it, as clearly shown in Fig. 12. The breech-block is formed with a longitudinal groove or slot r^3 in its under side to receive said finger r^2 , said groove terminating at the front end in a cam-surface r^4 , which coacts with a corresponding surface of the finger to shift the lever r upon a rearward movement of the breech-block and bring the dished head on said lever to pointing position in the chamber. As the breech-block nears the limit of its forward movement it encounters the dished head, which slopes off at the rear, so that the breech-block may pass easily over and displace it, the finger r^2 entering the slot r^3 .

The front end of the breech-block is circularly recessed to accommodate the flanged head of the cartridge, which when delivered in the position shown in Fig. 12 will be encountered by the breech-block in moving forward and will be slid along in its inclined position until its head passes the front ends of the lugs n^2 , whereupon said head will drop, so that it is wholly in front of the breech-block and will occupy the circular recess in the front end of the same when the latter closes the breech, said recess being concentric with the bore of the gun-barrel and the cartridge being guided into the latter by the arm o and lever r .

The breech-block is recessed or grooved in one side at the front, as shown at q in Figs. 14 and 15, to accommodate a pivoted catch q' , whose forward end is normally pressed inward to overhang the circular recess in the end of the breech-block by a spiral spring q^2 , arranged in a recess of the breech-block behind the heel of said catch. In the opposite side of the breech-block, but not diametrically opposite the catch q' , another and longer groove q^3 is formed, and another catch q^4 is arranged in said groove, being pivoted intermediate its length and its forward end being pressed inwardly by a spring q^5 , occupying a recess in the breech-block behind the heel of the catch. These two catches take over the flange of the cartridge when the breech-block closes the breech, and upon the rearward movement of the breech-block they will extract the spent shell, which is ejected through an opening in the side of the receiver. Ejection of the shell is accomplished by the fol-

lowing means: The heel of the catch q^4 is formed with a cam projection s^1 , and the end of a screw s^2 , entered through the side of the receiver, stands in the path of said cam projection, so that as the breech-block nears the end of its rearward movement the said cam projection will encounter the end of the said screw, and the forward end of the catch q^4 will be moved outwardly, so as to be disengaged from the flange of the shell, the catch q^4 , however, remaining engaged with said flange. In a horizontal slot s^3 made in one side of the receiver a little above the screw s^2 there is pivoted an abutment-piece s^4 in the form of a plate having a toe which projects into a groove s^5 , formed in the side of the breech-block, which groove is sufficiently deepened at its forward end to permit the said toe to project into the path of the shell, so that immediately upon the catch q^4 being released from the latter it will encounter this toe, with the obvious effect of causing the ejection of the shell end over end, as indicated in Fig. 14. The abutment-piece s^4 is pressed inwardly by a flat spring s^6 , inclosed by a suitable cover-plate s^7 , fastened to the side of the receiver, and the inward movement of said abutment-piece is limited by a pin s^8 , which encounters the side of the receiver.

The catch q^4 is not essential for extracting purposes, but is provided more particularly to guard against the shell being accidentally displaced before it reaches the proper position for ejection, and in this connection the location of this catch in a lower plane than the opposite catch q^1 (see Fig. 21) is important as being calculated to prevent upward tilting of the shell, such as might otherwise occur should it encounter the dished head r^1 or some other accidentally-interposed obstruction in the process of extraction.

The breech-block at its forward end is bored centrally to receive the firing-pin t , which is normally retracted by a spiral spring t^1 , occupying a recess back of the firing-pin bore and bearing at one end against one end of said recess and at the other end against a collar on the firing-pin, the rearward movement of the latter being limited by a screw t^2 , which stands in the path of said collar. Back of the recess which contains said spring the breech-block is bored out in larger diameter and contains the hammer comprising a circular head t^3 , fitting the enlarged bore and abutting the firing-pin, and a stem t^4 , surrounded by a spiral spring t^5 , confined between the hammer-head t^3 and a screw-plug t^6 , closing the rear end of the enlarged bore of the breech-block. The hammer-stem slides through this plug and has a cross-head t^7 , with a rounded lower end fitting the base of the chamber n and a finger t^8 in the slot p^2 , and the said cross-head is adapted to be engaged on its front side by a sear u , the tripping of which permits the hammer to act against the firing-pin. This sear

is pivoted at u^1 in a slot formed in the bottom of the receiver and has a heel u^2 depending substantially at right angles to it, and the upward movement of the sear is limited by a pin u^3 , encountering the under side of the receiver, the said sear being pressed upwardly by a flat spring u^4 , which is secured to the under side of the receiver and bears against the sear on the rear side of its pivot. The pivot u^1 for the sear is also the pivot for a breech-block locking-piece or latch u^5 , which has a depending heel u^6 confronting the heel u^2 of the sear, and said locking-piece is pressed upwardly through the slot in the bottom of the receiver by a flat spring u^7 , which is superior in strength to the spring u^4 , the upward movement being limited by a pin u^8 , which encounters the under side of the receiver. The locking-piece u^5 is formed with a cam projection u^9 , which when the lock is in its uppermost position, as shown in Figs. 1, 9, and 10, stands in line with an arm u^10 , depending from the block g^6 through the slot p^2 , the lower part of said arm being shaped to partially embrace the hammer-stem as a guide. The lower extremity of this arm is beveled, as shown at u^11 , for coaction with the beveled front side of the cam projection u^9 , so that upon the rearward movement of the rod g and before the collar m^4 encounters the collar p^3 the lock-piece, which normally stands behind the breech-block, as shown in Fig. 1, and prevents rearward movement of the latter, will be displaced. The breech-block is beveled on the lower side at the rear end, as shown at u^12 in Fig. 10, so as to readily pass over the lock-piece and its cam projection in moving rearwardly.

A handle v similar in form to a pistol-grip is fastened to the under side of the receiver and is chambered to contain an upstanding wedge v^1 , whose upper end enters between the heels u^2 and u^5 of the sear and lock-piece, the said wedge being pivoted to the free end of a trigger v^2 , pressed downwardly by a flat spring v^3 and having a finger-piece v^4 projecting through a slot in the grip and surrounded by a guard v^5 . So long as the trigger remains in its normal position, which is shown in Fig. 1 and indicated in Fig. 9, the gun will not operate, as the sear remains in position to prevent any action of the hammer, and when the wedge v^1 is in its lowermost position there is not sufficient of it interposed between the heels u^2 and u^5 to cause the upward movement of the latch or locking-piece under the influence of the spring u^7 to effect a disengagement of the sear from the hammer. However, upon drawing back the finger-piece v^4 the wedge is forced up between the said heels, and the spring u^7 being weaker than the spring v^3 the sear is displaced and the hammer released, whereupon the firing-pin is driven against the cartridge. A set-screw v^6 , entered through the rear side of the guard v^5 , regulates the amount of movement of the trigger necessary to force the wedge the requisite

- distance upward between the heels. So long as the wedge is interposed between the heel-pieces to the extent produced by manipulation of the finger-piece, the upward movement of the latch u'' , under the influence of the spring u^6 , will effect the disengagement of the sear from the hammer, so that each time the said latch locks the breech-block the hammer is released.
- 10 A brief review of the general operation of parts in a cycle of the gun's action will now be sufficient, coupled with statements of operation hereinbefore given relative to particular mechanisms.
- 15 The parts being in the relative positions shown in Fig. 1 and a belt of cartridges having been introduced through the side openings in the front part of the receiver, so that the first cartridge is in proper position to be
- 20 extracted from the belt, and the extractor-fingers m^6 having been previously retracted by manipulation of the handle i and then released so as to snap over the flanged head of the cartridge, the said handle is now drawn
- 25 back to the limit of its rearward movement, so as to extract the first cartridge from the belt and is then released, so that this cartridge will be introduced into the breech of the gun-barrel and the second cartridge
- 30 grasped by the extractor-fingers, and then the finger-piece v^4 is drawn back, which has the effect of elevating the wedge v' and forcing it between the heels u^2 and u^5 , thereby depressing the sear u , whereby the hammer is released,
- 35 so that it impinges upon the firing-pin. As soon as the ball passes the port c^6 gas travels back through the pipe e and operating upon the piston f drives the rod g and attached parts back, whereby the extractor-fingers m^6
- 40 are caused to pull a cartridge out of the belt and carry the same back under the arm o to the position shown in Fig. 2. The breech-block remains locked in its forward position until the ball has traveled a short distance beyond the port c^6 , and then the action of the collar m^4 against the collar p^3 causes the breech-block to move rearwardly, it having been previously unlocked by the action of the arm u^9 against the cam projection u^7 on the locking-piece u'' . In the rearward movement of the breech-block the lever r is tilted so as to bring the dished head thereof up into position to receive the ball end of the cartridge. The empty shell is drawn out of the breech by the
- 55 catches q' and q^4 and ejected through the side opening s in the receiver just as the limit of the rearward movement of the reciprocating structure is reached and while the fresh cartridge is still above the chamber formed between the breech and the breech-block, said cartridge having brought up against the shoulder formed by the front side of the lug p^6 , with its head lowered somewhat by contact with the arm o , but still above the breech-block and always farther forward than the same. Fig. 2 illustrates the relative positions of parts when the reciprocating structure is

at the limit of its rearward movement, and it will be understood that the feed-slide has moved outwardly, so that its dogs are behind the cartridge next but one to that extracted and ready to advance the next cartridge into the throat of the receiver. It will further be observed that the cross-head l^6 of the hammer has been carried back of the sear, so that upon moving forward it will encounter the same, whereby the hammer will be restrained and its spring compressed. The ball having issued from the muzzle and the gas having spent itself, the springs g^2 impel the rod g forward, and instantly the fingers m^6 leave the cartridge, and the wiper o^3 encounters the lug o^2 , and the arm o is thrown down and pushes the cartridge down sufficiently to bring it in front of the breech-block, where its head rests upon the lugs n^2 , while its ball end rests on the dished head of the lever r . The block g^6 encounters the collar p^3 , and thereupon the breech-block is moved forward and acts upon the cartridge to shove the same forward, and just after the ball has entered the breech the head of the cartridge passes the flanges n^2 and drops, so that it is wholly in front of the breech-block. The breech-block is driven home, and as the cartridge comes to a seat in the breech the extractor-catches snap over the flange of its head and the parts assume the normal position shown in Fig. 1, the feed-slide having moved in and entered a cartridge in the throat of the receiver, where it is seized by the fingers m^6 . The finger-piece v^4 being held in its backward position, the upward movement of the locking-piece u'' , under influence of the stronger spring u^6 , causes the downward movement of the sear u and the release of the hammer, so that the cartridge which has been introduced into the breech of the gun-barrel is immediately discharged.

It will thus be seen that so long as the belt supplies the cartridges and the finger-piece v^4 is held back the cartridges will be discharged in rapid succession automatically.

In the modified construction shown in Figs. 30 to 35 the rear end of the receiver, which might be termed the "gun-stock," is shown provided with handles w , fastened on opposite sides of the same and projecting from the rear end thereof, so that they can be conveniently grasped by the two hands of the operator, and the pistol-grip on the under side is dispensed with, the trigger mechanism being modified, as presently described. Adjacent to one of these handles there is pivoted to ears on the block closing the rear end of the receiver a thumb-piece w' , which bears against a cap w'' , screwed on the rear end of a rod w^3 , sliding through the said block and carrying at its forward end a cross-pin w^3 , engaged with the hooked upper end of a bifurcated arm w^4 , which constitutes one member of a bell-crank lever, the other member w^5 of which is jointed by a slot-and-pin connection with a pendent wedge w^6 , a spiral spring w^7 being attached to the arm w^4 at one end and

to a fixed support at the other end and normally holding the wedge w^6 elevated and the rod w^2 pushed back. In the former construction, where the locking-piece or latch and the sear were located on the under side of the breech-block, the locking-piece engaged the rear end of the latter and the hammer projected rearwardly from the breech-block; but in this modified construction the locking-piece and sear are arranged above the breech-block and the hammer is wholly contained within the latter. The reference-letter x designates the hammer-stem, and x' the cross-head on the same, which has a lug x^2 , traveling in a longitudinal slot x^3 in the upper side of the breech-block, a spiral spring x'' being interposed between the head x' and the plug which closes the rear end of the breech-block. As in the former construction the latch and sear have a common pivot, which is designated by the letter y , but the position of the parts is reversed, those portions which engage the breech-block and hammer-head being on the lower side of the pivot and the parts which are engaged by the wedge w^6 being on the upper side of the pivot. The locking-piece comprises an arm y' , which is adapted to enter a notch y'' in the upper side of the breech-block and lock the same in its forward position, an upwardly-extending arm y^3 occupying a position on the rear side of the wedge w^6 , and an arm or lug y^4 , which is positioned for contact with a lug y^4 on the under side of the rod g , this latter lug corresponding with the arm w^9 in the former construction and operating to release the lock by reason of its contact with the upper forward corner of the lug y^3 . The top surface of the breech-block is beveled for a short distance from the front end of the notch y'' , as shown at y^5 , so that in the rearward movement of the breech-block this beveled surface may operate against the arm y' of the locking-piece and elevate the same, so that when the forward portion of the top surface of the breech-block is supporting said arm of the locking-piece the lug y^3 will be sufficiently depressed to permit the passage of the lug y^4 on the rod g when the latter advances. The spring which depresses the arm y' of the locking-piece is indicated at y^6 , said spring being suitably fastened to an appropriate portion of the receiver and bearing upwardly against a lug y^5 , projecting rearwardly from the boss of the locking-piece. The sear comprises an arm y^8 , adapted to enter the slot x^3 and stand in front of the lug x^2 on the hammer-head x' , as clearly shown in Fig. 31, and also an upstanding arm y^9 , standing in front of the wedge w^6 , opposite the latch-arm y^2 . A flat spring y^{10} is suitably secured to an appropriate part of the casing and bears upwardly against the lower end of the arm y^9 , so as to press the arm y^8 downwardly into position for engagement with the lug on the hammer-head, a pin y^{12} by abutting the surface at one side of the slot limiting the movement of the sear. Said

spring y^{10} is inferior to the spring y^6 , which presses the lock-arm y' downwardly, and it will therefore be seen that by pressing the thumb-piece w^1 inwardly, and thereby forcing the wedge w^6 downwardly, the sear will be disengaged from the hammer-head and that by holding said thumb-piece pressed inwardly each time the lock-piece moves into locking position the sear will be disengaged from the hammer-head, the action in this respect being substantially similar to that of the previously-described devices. In the modified form the lock-piece is slotted under the lug y^3 , and the arm y^8 of the sear occupies the slot and is offset from the arm y^9 , so that the latter can confront the arm y^2 of the locking-piece, the pivot-pin extending through the arm y^8 , where it occupies the slot, as shown in Fig. 34.

Figs. 36 and 37 illustrate a modified construction of cartridge-feeding mechanism in which a lever z is employed in conjunction with the cam-piece k^6 , which lever is pivoted at its end, as shown at z' , having no tailpiece, such as that employed in the former construction. Instead of a flat spring, such as employed in the former construction, the slide is moved outwardly by a retractile spiral spring z^2 , which is connected at one end to the inner end portion of the slide and occupies a recess z^3 in the top of the casing j^3 , being connected to a plug z^4 , closing the outer end of said recess.

In either form of receiver access may be had for the purpose of removing a cartridge should one become stuck in transit from the belt to the breech through an opening b^9 in one side of the receiver, which opening is adapted to be closed by a slide b^{10} . A similar slide b^{12} is arranged to close the opening in the opposite side of the receiver when the gun is not in use.

It is to be understood that while the forms of means here illustrated are admirably adapted to the fulfilment of the object primarily stated, yet the invention can be embodied in other forms, and hence I do not confine myself in the following claims to the details of construction herein shown and described.

In the feed mechanism the dogs might be arranged to act against the cartridge immediately to be extracted; but I prefer to so locate these dogs that they will act against the next cartridge to the one immediately to be extracted for the reason that the cartridge is freer for extraction than if still engaged by the dogs when being extracted from the belt. Again, instead of a U-shaped feed-slide, such as here shown, a solid block or plate might be employed; but I prefer the form shown as better calculated to resist a twisting tendency induced by the lever and cam mechanism.

Having thus fully described my invention, what I claim as new, and desire to secure by Letters Patent of the United States, is—

1. In a gas-operated rapid-fire gun, the com-

- bination of a receiver having a screw-threaded boss on its forward end, a barrel projecting from the receiver and supported thereby, a gas-conduit communicating with said barrel in the rear of its muzzle and extending back to the receiver, a water-jacket embracing said conduit and barrel and having a flanged inner end abutting the boss on the receiver, and a coupling-collar taking over the flange of the jacket and engaging the screw-threads of said boss.
2. In a gas-operated rapid-fire gun, the combination with the receiver, the barrel and the gas-conduit, of a water-jacket embracing said conduit and barrel and detachably coupled to the receiver and having lugs which engage opposite sides of the gas-conduit to hold the jacket from turning in either direction.
3. In a gas-operated rapid-fire gun, a gas-conduit communicating with the barrel at the forward part of the same and extending rearwardly therefrom, a cylinder compounded with said conduit, a perforated plug closing the rear end of the cylinder, a piston in said cylinder, and loading mechanism actuated by said piston.
4. In a gas-operated rapid-fire gun, the combination of a barrel having a screw-threaded socket on one side and a port through the bottom of said socket, a gas-conduit in the form of a pipe having a transversely-apertured and interiorly-screw-threaded head, a plug screwing into said head and into the socket of the barrel and having a bore communicating with the port in the bottom of said socket and also having a port to register with the pipe-bore, a cylinder compounded with said pipe, a piston in said cylinder, and loading mechanism actuated by said piston.
5. In a gas-operated rapid-fire gun, the combination of a barrel having a screw-threaded socket on one side and a port through the bottom of said socket, a gas-conduit in the form of a pipe having a transversely-apertured and interiorly-screw-threaded head, a plug screwing into said head and into the socket of the barrel and having a bore communicating with the port in the bottom of said socket and also having a port to register with the pipe-bore, a valve or choker in the form of a screw entered through one side of the pipe-head and having an end portion protruding into the bore of the plug, a cylinder compounded with the said pipe, a piston in said cylinder, and loading mechanism actuated by said piston.
6. In a rapid-fire gun, the combination of a reciprocatory actuator having a laterally-projecting cam-incline tapering as it extends forward, a horizontally-vibratory lever arranged laterally beyond the said cam-incline and having a roller to coact therewith in effecting outward movement of the lever under forward movement of the actuator, and a cartridge-feeding slide coupled to said lever and equipped with dogs adapted to successively engage cartridges carried in a belt which passes through the receiver of the gun, provisions existing by virtue of which the lever and slide are retracted when the actuator moves rearwardly, substantially as described.
7. In a rapid-fire gun, the combination of a reciprocatory actuator having a laterally-projecting cam-incline tapering as it extends forward, a horizontally-vibratory lever arranged laterally beyond the said cam-incline and having a roller to coact therewith in effecting outward movement of the lever under forward movement of the actuator, and a cartridge-feeding slide coupled to said lever and equipped with dogs adapted to successively engage cartridges carried in a belt which passes through the receiver of the gun, together with a spring arranged to retract the lever and slide upon rearward movement of the actuator.
8. In a rapid-fire gun, a receiver having openings in opposite sides and a passage-way between said openings, one of the latter being of sufficient width to pass a cartridge crosswise and the other being of less width and the receiver having internal shoulders at opposite sides of the passage-way for the cartridge to abut, an upwardly-pointing pin standing out from the face of one of said shoulders, means for feeding a cartridge against the shoulders and under said pin, and means for removing the cartridge lengthwise from its position against the shoulders.
9. In a rapid-fire gun, the combination of a receiver, a reciprocatory actuator therein having a cam-piece on one side and a roller on the opposite side running along a wall of the receiver, and cartridge-feeding devices coöperating with said cam-piece to actuate a belt of cartridges step by step under reciprocation of the said actuator.
10. In a rapid-fire gun, the combination of a reciprocatory actuator carrying a pair of extractor-fingers transversely disposed relative thereto, spring-pressed toward each other, movable in a plane substantially at right angles to the plane of movement of the actuator, and having oppositely-inclined confronting side faces adapted to encounter a cartridge-head in the feed-throat under one direction of movement of the actuator, longitudinal edges of said fingers snapping past the flange of the cartridge and extracting the latter from the throat upon the reverse movement of said extractor; and means for feeding cartridges into the throat.
11. In a rapid-fire gun, the combination of a reciprocatory actuator carrying a pair of extractor-fingers spring-pressed toward each other and having oppositely-inclined confronting faces adapted to encounter a cartridge-head in the feed-throat under one direction of movement of the actuator, said fingers snapping by the flange of the cartridge and extracting the latter from the throat upon the reverse movement of said actuator, and

having lugs on their rear edges to hold the cartridge down; and means for feeding cartridges into the throat.

12. In a rapid-fire gun, the combination of a receiver having a cartridge-belt passage extending transversely through its front portion and a throat to receive the cartridges one by one, an upwardly-pointing guard-pin standing out toward the entrance to the throat at one side of the throat and holding a cartridge in proper position therein, a reciprocatory actuator having means for extracting the cartridge from the belt, and means for feeding the cartridges into the throat.

13. In a rapid-fire gun, the combination of a receiver having a feed-throat, means for feeding cartridges crosswise into said throat, a reciprocatory actuator having a block recessed in its sides and across its top, fingers pivoted in the side recesses and having depending portions with oppositely-inclined confronting faces, and a spring in the top recess of the block bearing upon the upper ends of the fingers and pressing their depending portions toward each other, the confronting faces of the latter adapted to encounter the flanged head of the cartridge in the throat whereby the fingers are spread apart and snap over the flange of the cartridge, substantially as and for the purpose described.

14. In a rapid-fire gun, the combination of a receiver having a throat for cartridges, a reciprocatory actuator having means for extracting the cartridge from said throat, a cartridge depressing and pointing arm normally standing on an upward inclination and beneath which arm the cartridge is carried by the extracting means, and means carried by the reciprocatory actuator for depressing said arm upon the advance of the actuator, substantially as and for the purpose described.

15. In a rapid-fire gun, the combination of a receiver having a throat for cartridges, a reciprocatory actuator having means for extracting the cartridge from said throat, a cartridge depressing and pointing arm normally standing on an upward inclination and beneath which arm the cartridge is carried by the extracting means, said arm having an upper standing lug, and a laterally-movable spring-pressed wiper on the reciprocatory actuator positioned to encounter said lug with one side edge in the rearward stroke of the actuator and be thereby displaced and to encounter the lug with its forward end in the advance of the actuator thereby depressing the arm, substantially as and for the purpose described.

16. In a rapid-fire gun, the combination of a receiver having a cartridge-throat at its forward part, a reciprocatory actuator having means for extracting a cartridge from the throat, a breech-block engaged with said actuator so as to be reciprocated thereby and grooved in its upper side at the front, a cartridge depressing and pointing arm pivoted to a stationary support and having a heel-piece engaging the breech-block whereby

when the latter is advanced the arm is held in an upward-inclined position where the cartridge can pass under it, and when the breech-block is retracted said arm may drop by reason of the groove in the breech-block receiving the heel-piece of the arm; and means carried by the actuator for throwing down the said arm, substantially as and for the purpose described.

17. In a rapid-fire gun, the combination of a receiver having a feed-throat at its forward part, a reciprocatory actuator having spring-pressed fingers to seize a cartridge in said throat, a pivoted arm standing normally in an upward-inclined position where the said spring-fingers will pass on either side of it when the actuator moves rearwardly, and means carried by the actuator for depressing said arm when said actuator advances and the cartridge has been delivered under the arm.

18. In a rapid-fire gun, the combination of a receiver having a throat for cartridges, a reciprocatory actuator having means for extracting the cartridge from said throat, a cartridge depressing and pointing arm normally standing on an upward inclination and beneath which arm the cartridge is carried by the extracting means, means carried by the reciprocatory actuator for depressing said arm upon the advance of the actuator, a lower cartridge-pointing arm or lever, and means for elevating the latter to receive the ball end of the cartridge.

19. In a rapid-fire gun, the combination of a receiver having a throat for cartridges, a reciprocatory actuator having means for extracting the cartridge from said throat, a cartridge depressing and pointing arm normally standing on an upward inclination and beneath which arm the cartridge is carried by the extracting means, means carried by the reciprocatory actuator for depressing said arm upon the advance of the actuator, a lower cartridge-pointing arm or lever, and a breech-block engaged with the actuator so as to be reciprocated thereby and grooved in the under side to receive the heel of said lower cartridge-pointing lever, the forward end of said groove operating on the backward movement of the breech-block to tilt the said lever to position for receiving the ball end of the cartridge, substantially as and for the purpose described.

20. In a rapid-fire gun, the combination of a receiver having a cartridge-throat at its forward part, a reciprocatory actuator having means for extracting a cartridge from the throat, a breech-block engaged with said actuator so as to be reciprocated thereby and grooved in its upper and lower sides, upper and lower cartridge-pointing arms having heels for engagement with said grooves respectively, the breech-block in its forward position holding the lower arm depressed, and the upper arm elevated so that the cartridge can pass under it, and means carried by the

actuator for depressing the upper arm on the forward stroke of the actuator, an accompanying forward movement of the breech-block causing the front end of its lower groove 5 to elevate the cartridge-receiving end of the lower arm.

21. In a rapid-fire gun, the combination of a receiver having a feed-throat at its forward part, a reciprocatory actuator having means 10 for extracting cartridges one by one from said throat, a breech-block engaged with the actuator so as to be reciprocated thereby, means for delivering the cartridge in front of the said breech-block, a guide or pointing-lever 15 to receive the ball end of the cartridge when so delivered, and means for shifting said lever, substantially as described.

22. In a rapid-fire gun, the combination of a receiver having a feed-throat at its forward 20 part, a reciprocatory actuator having means for extracting cartridges one by one from said throat, a breech-block engaged with the actuator so as to be reciprocated thereby, and grooved in its under side, means for delivering 25 the cartridge in front of said breech-block, and a pointing-lever having a head to receive the ball end of the cartridge when so delivered and having a heel to enter the groove in the under side of the breech-block, the forward 30 end of said groove operating to tilt the lever and bring its head up into position for receiving the ball end of the cartridge.

23. In a rapid-fire gun, the combination of a receiver having a discharge-opening in one 35 side, a grooved breech-block reciprocating in said receiver and past said opening, spring-pressed extractor-catches in grooves of said breech-block, one located in a lower plane than the other, and having a cam projection, an 40 abutment in the receiver for said cam projection to encounter, and an ejector on the receiver and projecting into a groove in the breech-block where the extracted shell will encounter it upon being disengaged from the 45 catch having the cam projection.

24. In a rapid-fire gun, the combination of a receiver having a chamber running back from the barrel and a discharge-opening in one side of the chamber, a breech-block in 50 said chamber, spring-pressed extractor-catches carried by the breech-block, one located in a lower plane than the other, means for tripping that one of said catches, an ejecting abutment for the cartridge to encounter 55 upon disengagement from said catch, and means for reciprocating the breech-block.

25. In a rapid-firing gun, the combination of a reciprocatory breech-block, arranged to be moved backward by force resulting from 60 a discharge, a spring arranged to impel said breech-block forward, a firing-pin in the breech-block, a hammer carried by the breech-block and spring-actuated into engagement with the firing-pin, a sear arranged to engage 65 said hammer and hold it while the breech-block moves forward, a latch arranged to lock the breech-block in its forward position, means

for automatically displacing said latch, and trigger mechanism for tripping the sear and establishing a connection between the latter and the latch, substantially as described. 70

26. In a rapid-fire gun, a reciprocatory structure adapted to be actuated in one direction by force resulting from a discharge and in the opposite direction by spring-pressure, said 75 structure comprising a member receiving the direct impact of the retracting force and having abutment-pieces and a cam-piece, a breech-block having a part extending between the said abutment-pieces, a sufficient space being provided to permit movement of the said member having the abutment-pieces independent of the breech-block, a firing-pin in the breech-block, and a hammer carried by the latter and spring-actuated toward the firing-pin; in combination with a sear adapted 80 to engage said hammer and hold it while the breech-block advances, a latch arranged to lock the breech-block in its forward position and adapted to be displaced by the cam-piece 85 on the first-named member of the reciprocatory structure, and trigger mechanism for tripping the sear and establishing a connection between the same and the latch, substantially as described. 90

27. In a gas-operated gun, the combination of a reciprocatory actuator, a breech-block engaged therewith, a spring-pressed hammer carried by the breech-block, a locking-piece in the form of an automatic catch operating 100 independently of the actuator-reciprocating means and adapted to hold the breech-block against the breech end of the gun-barrel; a sear, and connections between the locking-piece and sear whereby the latter is tripped 105 by the movement of the former into locking position. 95

28. In a gas-operated gun, the combination of a reciprocatory actuator, a breech-block engaged therewith, a spring-pressed hammer 110 carried by the breech-block, a locking-piece in the form of a spring-pressed catch for holding the latter against the breech end of the gun-barrel, a sear, and connections between the locking-piece and sear whereby the latter is tripped 115 by the movement of the former into locking position.

29. In a gas-operated gun, the combination of a reciprocatory actuator, a breech-block engaged therewith, a spring-pressed hammer 120 carried by the breech-block, a locking-piece for holding the latter against the breech end of the gun-barrel, a sear, and trigger mechanism establishing a connection between the lock and sear whereby the latter is tripped 125 by movement of the former into locking position.

30. In a gas-operated gun, the combination of a breech-block, a spring-pressed hammer carried thereby, a locking-lever spring-pressed 130 to locking engagement with the breech-block and having a heel a sear pivoted concentrically with said lock-lever and having a heel confronting that of the latter, said sear being

pressed to hammer-engaging position by a spring inferior to that which actuates the locking-lever, a filler-piece or wedge between said confronting heels, manipulative means connected with said wedge, a reciprocatory actuator engaged with the breech-block but movable independently thereof, and means carried by said actuator for tripping the locking-lever.

31. In a gas-operated gun, the combination of a breech-block, a spring-pressed hammer carried thereby, a locking-lever spring-pressed to locking engagement with the breech-block and having a heel, and a cam protuberance, a sear pivoted concentrically with said locking-lever and having a heel confronting that of the latter, said sear being pressed to hammer-engaging position by a spring inferior to that which actuates the locking-lever, a filler-piece or wedge between said confronting heels, manipulative means connected with said wedge, and a reciprocatory actuator engaged with the breech-block but movable a distance independently thereof and having a projection to act against the cam protuberance of the locking-lever, substantially as and for the purpose described.

32. In an automatic rapid-fire gun, a reciprocatory actuator having a bifurcated arm, and a slide-rod having a handle and a head to abut the front side of the bifurcated arm and a cross-piece to abut the rear side of said bifurcated arm when the rod is turned, substantially as described.

33. In a rapid-fire gun, the combination of a receiver having a transverse passage for a belt of cartridges and a throat to receive the cartridges one by one, while in the belt, a feed-slide having dogs arranged to move a car-

tridge into the throat by operating against a cartridge farther removed from the throat, means for reciprocating the slide, and means for extracting from the belt the cartridge in the throat.

34. In a rapid-fire gun, the combination of a reciprocatory actuator having a bifurcation, a manipulative slide-rod extending through said bifurcation and having a head to encounter one side of the same, said rod also having a cross-piece of dimensions to pass through the bifurcation under one adjustment of the rod and to take over the side of the bifurcation opposite that which the head abuts, when the rod is turned to another adjustment; and cartridge feeding, loading, firing and extracting means in operative connection with the actuator.

35. In a rapid-fire machine-gun, the receiver having the longitudinally-disposed ribs or guides on opposite sides thereof, in combination with the interposed reciprocatory bar bearing against said guides and having bifurcated portions embracing the same; said bar having a forward extension and cam portions thereon for engaging and actuating the feed-slide-actuating lever, and also provided with means for actuating the cartridge-depressing arm, the breech-block lock, and breech-block, and with means for extracting a cartridge from the cartridge-belt when the actuator moves rearward; substantially as described.

In testimony whereof I affix my signature in presence of two witnesses.

VICTOR P. DE KNIGHT.
